UNITED STATES PATENT OFFICE.

HERBERT H. STEELE, OF SYRACUSE, NEW YORK, ASSIGNOR TO THE MONARCH TYPEWRITER COMPANY, OF SYRACUSE, NEW YORK, A CORPORATION OF NEW YORK.

TYPE-WRITING MACHINE.

No. 892,627.

Specification of Letters Patent.

Patented July 7, 1908.

Application filed December 1, 1905. Serial No. 289,789.

To all whom it may concern:

Be it known that I, HERBERT H. STEELE, citizen of the United States, and resident of Syracuse, in the county of Onondaga and State of New York, have invented certain new and useful Improvements in Type-Writing Machines, of which the following is a specification.

My invention relates to typewriting machines and more particularly to carriage stop mechanism therefor.

One of the objects of my invention is to provide efficient means for preventing undue shock when the carriage is violently moved to the right to begin a new line of writing.

A further object of my invention is to provide simple and efficient means for preventing the shock which ordinarily results when the carriage is violently returned to the right from being transmitted to the feed rack or carriage feed mechanism.

A still further object of my invention is to assure the proper positioning of the carriage when it is returned to the right.

Another object of my invention is to provide efficient stop mechanism for affording an actuation of the alarm and line lock mechanisms.

To the above and other ends which will hereinafter appear, my invention consists in the features of construction, arrangements of parts and combinations of devices to be hereinafter described and particularly pointed out in the appended claims.

In the accompanying drawings wherein like reference characters indicate corresponding parts in the various views, Figure 1 is a fragmentary front elevation of the upper portion of the typewriting machine with parts omitted and parts in section, the view showing the features of my invention applied to the machine. Figs. 2, 3 and 4 are like views of the same, showing different dispositions of the parts. Fig. 5 is an enlarged vertical front to rear sectional view of the same taken on the line $x-x$ of Fig. 1 and looking in the direction of the arrow at said line. Fig. 6 is an enlarged detail side elevation, partly in section, of the pivoted stop, the view showing the manner of mounting the same on the carriage. Fig. 7 is an enlarged detail sectional view showing the stop rod and the margin stop mounted thereon.

I have shown my invention applied to a Monarch machine to which my invention

may be applied without changing the structural features of such machine, but the invention may obviously be applied to other forms of typewriting machines.

Corner posts 1 of the machine support a top plate 2 to which upwardly extending standards or brackets 3 are secured, one near each side of the machine. These brackets support fixed rails 4 secured in place by screws 5, and the rails have oppositely disposed grooves 6 therein for co-operation with anti-friction balls or rollers 7. A carriage 8 is provided with oppositely disposed grooved rails 9 that likewise co-operate with the anti-friction balls 7 to support the carriage in place and to afford a travel thereof from side to side of the machine. The carriage supports a cylindrical platen 10 and carries a combined line spacing and carriage restoring arm or lever 11 which projects forwardly from the carriage.

A link 12, actuated by the universal bar in the usual manner, is connected at its upper end to an arm 13 that extends forwardly from a rock shaft 14 mounted on a fixed bracket 15 secured to the top plate of the machine. The rock shaft has an upwardly extending arm 16 which carries feed dogs 17. The arms 13 and 16 and the rock shaft 14 constitute a dog rocker which is restored to its normal position by a spring 18 connected at one end 19 to the bracket 15 and at its other end 20 to the rock shaft 14. The feed dogs co-operate with an escapement wheel 21 which is operatively connected in the usual manner to a shaft supported in a bearing 22 which is secured to the top plate of the machine. The forward end of the shaft of the escapement wheel has a pinion 23 secured thereto. A carriage feed rack 24 meshes with the feed pinion 23 and is connected at its ends to arms 25 which extend forwardly and are secured at their forward ends to rock shafts 26, said rock shafts being adapted to turn in bearings 27 formed in the carriage. Each rock shaft extends entirely through its bearing and the outer end thereof has a forwardly extending release lever or arm 28 secured thereto by a headed screw 29. The forward end of each release lever or arm 28 is provided with a finger piece 30 by which the associated rock shaft 26 may be turned and the feed rack 24 elevated to disengage it from its co-operating feed pinion, the upward movement of the feed rack being limited by

projections 25^a on the arms 25 contacting with the upper carriage rail 9. It should be understood that one of the release arms 28 is provided at each end of the platen and is connected to a rock shaft 26 which in turn is connected with the feed rack through the rearwardly extending arm 25. When pressure is released on the depressed carriage release lever 28, the feed rack will be forced 10 into engagement with the feed pinion by a restoring spring 24^a secured at one end to the feed rack by a screw 24^b and bearing at its free end against the upper carriage rail 9 or against a part projecting therefrom.

Projecting upwardly from the upper fixed carriage rail 4 are bearing lugs 31 which are perforated to form bearings for cylindrical bearing portions 32 carried by a stop rod 33. The cylindrical bearing portions 32 are extended beyond the bearing lugs 31 and each cylindrical portion is provided with a finger piece 34 by which the stop rod may be turned. A coiled spring 35 surrounds one of the bearing portions 32 and is connected at one end to the associated bearing lug and at its opposite end to the associated finger piece 34, so that the rod is restored to its normal position by the springs 35, a stop 36 being provided to limit 30 the turning movement of the stop rod in its movement back to normal position, said stop 36 being carried by the stop rod and adapted to bear on the upper carriage rail. The stop rod 33 is notched in its forward 35 face, the notches being situated letter space distances apart and the upper face of the stop rod is provided with a scale (not shown) which corresponds to the carriage scale. A margin stop 37 has a carrier 38 which is in the nature of a slide that partly surrounds the stop rod and is adapted to move longitudinally thereon in order to afford an adjustment of the stop to different positions along the rod. A latch 39 is adapted 40 to engage in any of the notches 40 in the stop rod to lock the margin stop against longitudinal movement thereon. This latch 39 constitutes part of a finger piece 41 which is pivoted to the stop carrier at 42, so that 45 the engaging portion of the latch may be thrown out of the notch to afford an adjustment of the stop along the stop rod. An expansion spring 43 is seated in an opening in the part 41 of the latch and bears at its 50 upper end against the latch and at its lower end against the stop carrier in order to normally maintain an engagement between the latch and the stop rod. When the finger piece 41 is depressed against the tension of 55 the spring 43 the latch is released from engagement with the notch 40 in which it is seated. A carrier 38^a for the alarm and line lock stop is constructed in essentially 60 the same manner as the carrier 38 and the same means are provided for locking the car-

rier in its adjusted position on the stop rod. The carrier, however, has an alarm stop 44, an initial line lock stop 45 and a final stop 46. The construction thus far described is the same as that employed in the Monarch machine and further detailed description thereof is not deemed necessary. 70

By referring to Fig. 6 it will be seen that a headed shouldered screw 47 is received at its threaded end 48 in an opening in the lower carriage rail 9 and constitutes a pivot for a stop 50. This stop is in the nature of an angular lever, one arm of which extends upwardly into the path of the margin and alarm and line-lock stops, whereas the other 80 arm 51 of the lever extends at substantially right angles to the upwardly extending arm and may be termed an actuating arm or member. This arm has an anti-friction roller 52 pivoted thereto at 53 and said roller is adapted to bear upon a bar 54 which is approximately as long as the carriage and has rearwardly projecting arms 55 at the ends thereof, said arms being pivoted by shouldered screws 56 to the ends of the lower fixed carriage rail 4. Thus the bar 54 and arms 55 constitute what may be termed a swinging bail pivoted on the screws 56 to swing up and down, the upward movement of the bail being limited by a finger 90 54^a thereon, which coöperates with the lower fixed rail 4. The bail carries a rearwardly projecting pin 54^b that extends under and coöperates with one arm 54^c of a line lock lever pivoted at 54^d to the fixed rail 4 to which the bail is pivoted. The other arm 54^e extends downwardly and is provided with a hook-like end 54^f which is adapted to engage under a projection 54^g carried by the link 12 through which motion is transmitted from the universal bar (not shown) to the dog rocker 14. The bail 54— 100 55 carries a rearwardly projecting arm 57 which is provided with a bell hammer 58 at the rear end thereof. A bell 59 is secured to a spindle 60 that is carried by the frame of the machine. 105

From an inspection of Figs. 1 and 5 it will be seen that a wire spring 61 is secured at one end to the lower fixed carriage rail 4 by a screw 62, whereas the free end of the spring extends beneath and coöperates with a pin 63 which projects laterally from the bail 54. The tension of the spring 61 is exerted to maintain the bail 54 in its elevated position, but when the pivoted stop 50 is turned to the position shown in Fig. 4, by contact with the alarm stop 44, it is effective to depress the bail and raise the bell hammer 58. When the pivoted stop is released from this position the bail will be restored to its normal position and the hammer 58 will strike the bell 59 and sound the alarm. A further movement of the carriage to the left brings the line-lock stop 45 into coöperation with the 110 115 120 125 130

lever 50, causing a further movement of the upper end thereof to the right than was effected by the stop portion 44 and consequently the bail 54—55 will be depressed to a greater extent allowing the line-lock lever to turn by its own weight from the normal position shown in Fig. 1 to a position where the hook-like portion 54^c thereof will extend beneath the projection 54^e, thus locking the 10 dog rocker against movement. The construction and operation of the line-lock and alarm devices controlled by the bail 54—55 is similar to the corresponding devices employed in the Monarch machine and further 15 description thereof is deemed unnecessary.

For the purposes of the present invention it is immaterial what character of line-lock or alarm mechanism the line-lock and alarm actuating device or bail 54 may coöperate 20 with. An auxiliary lever 64 is also pivoted on the pivot screw 47 and is held against longitudinal displacement on the pivot screw by a hub 65 formed on the pivoted stop 50. This auxiliary lever 64 has a rearwardly bent 25 end 66 (see Fig. 5) which rests on the lower carriage rail and extends beneath the free end of a spring 67 which is secured to the feed rack by a screw 68 and extends longitudinally of said feed rack. The tension of the 30 spring is exerted downwardly and is limited in its downward movement by a pin or stop 69 which projects laterally from the feed rack and extends beneath the spring. The downward tension of the spring is maintained by a pin 70 which projects from the 35 feed rack above the spring near the screw 68. A pin 71 extends laterally from the auxiliary lever 64 and projects above the arm 51 of the pivoted stop so that an upward movement of the 40 arm 51 will carry the auxiliary lever 64 up with it. A coiled spring 72 surrounds the hub of the pivoted lever 50 and is connected at one end to the auxiliary lever 64 and at its opposite end to the pivoted stop. The 45 tension of this spring is always exerted to press or turn the stop lever 50—51 from right to left and to press or turn the pivoted lever 64 downwardly, thus pressing the pin 71 against the arm 51, as shown in Fig. 1, so that the 50 lever 50—51 and the lever 64 may turn together about the pivot screw 47 without this motion being resisted by the spring 72; but if the stop 50—51 be turned toward the right, as shown in Fig. 4, the arm 64 being held 55 against motion by the engagement of the arm 66 with the carriage rail, the arm 51 moves away from the pin 71, and the spring 72 tends to restore the lever 50—51 to normal position. In the normal disposition of the 60 parts the upright arm of the pivoted stop 50 is disposed as illustrated in Fig. 1, and bears against an end of a plunger 73 provided with a stem 74 that extends through a cylinder 75 and projects at its free end through an 65 opening in the head of the cylinder. The

projecting end of the stem is threaded for co-operation with a nut 76 which constitutes a stop that limits the movement of the plunger to the right and thus determines the normal position of the pivoted stop 50 and a locking nut 77 is employed to secure the nut 76 in its adjusted position. A coiled expansion spring 78 surrounds the stem of the plunger and bears at one end against the plunger 73 and at its opposite end against the head of the 70 cylinder. The cylinder 75 has rearwardly extending ears 79 formed thereon for co-operation with an ear or lug 80, which projects forwardly from the upper carriage rail 9 and a rivet 81 extends through openings in the 75 ears 79 and 80 to rigidly secure the cylinder to the carriage. It will be understood that the spring pressed plunger 73 constitutes an elastic or spring buffer against which the pivoted stop bears to limit the movement 80 thereof in its turning movement from right to left and to normally maintain the stop against displacement around its pivot from right to left, except as hereinafter pointed out. 90

In the operation of the machine the carriage travels in the direction of its feed from right to left, as indicated by the arrow on the carriage in Fig. 1, and during this movement the stop 50 is maintained in the position 95 shown in Fig. 1 until the end of the line is approached and the upper end of the upright arm of the stop is brought into contact with the alarm stop 44 and the pivoted stop is moved around its pivot by the continued 100 movement of the carriage to the position shown in Fig. 4. During this pivotal movement of the stop 50 the auxiliary lever 64 remains in its normal position being supported 105 by the lower carriage rail 9 and is unaffected by the movement of the pivoted stop. The movement of the stop 50 around its pivot from the position shown in Fig. 1 to that indicated in Fig. 4 is effective to depress the bail 54 and a still further movement of the 110 carriage is effective to release the pivoted stop from the alarm stop 44 and the pivoted stop will be vibrated so as to bring the upper end thereof into contact with the line-lock stop 45. This sudden release of the pivoted 115 stop allows the bail 54 to be suddenly elevated, thereby actuating the hammer and sounding the alarm. A still further movement of the carriage to the left turns the pivoted stop around its pivot, again depressing the bail 54 and maintaining it in the depressed position and actuating the line-lock mechanism. In the movement of the carriage back to start a new line of writing it is moved in the direction of the arrow in Fig. 2, 120 thus bringing the upper end of the pivoted stop, which in this instance acts as a margin stop, into contact with the margin stop 37 and if the impact between the stops 50 and 37 is slight the pivoted stop may not be dis- 130

placed from its normal position, shown in Fig. 1. In other words, if the impact between the stops 50 and 37 is insufficient to displace the plunger 73 or to overcome the tension of the spring buffer then the pivoted stop will remain in its normal position. If, however, the operator should move the carriage back to the right with considerable force the impact between the stops 50 and 37 will displace the spring buffer, as shown in Fig. 2, by moving the spring stop around its pivot and against the resistance offered by the spring buffer. This movement is effective to elevate the arm 51 on the pivoted stop which, however, does not effect an operation of the bail 54, the bail remaining in its normal position. The upward movement of the arm 51 carries with it the auxiliary lever 64 and the rack is elevated through the spring connection between the auxiliary lever and the rack to disengage the rack from its feed pinion. If the impact between the stops is only sufficient to move the pivoted stop to the position indicated in Fig. 2, for instance, then the rack will be elevated without deflecting the spring 67 because the tension of the spring 67 is sufficient to overcome the weight of the rack and the tension of the rack restoring spring 24^a without being raised off the pin 69. If, however, a greater force is employed to restore the carriage and the impact between the stops is such that the pivoted stop will be moved to the position indicated in Fig. 3, for instance, then the further movement of the auxiliary lever 64 will deflect the spring 67 against its tension, thus enabling further movement of the stop and auxiliary lever to take place without effecting a further upward movement of the feed rack and at the same time interposing an additional resistance of the tension of the spring 67 to the pivotal movement of the stop 50 by the impact between the stops 50 and 37. It will thus be seen that the extent of pivotal movement of the stop 50 by contacting with the margin stop 37 depends upon the force employed to restore the carriage. When the shock of the impact between the stops has been absorbed in the manner described the spring buffer, the rack restoring spring 24^a, and possibly the spring 67 will tend to restore the pivoted stop and its associated parts to their normal positions, thereby reestablishing an engagement between the feed rack and its pinion.

From the foregoing description it will be understood that a pivotal movement of the stop 50—51 which is effective to disengage the feed rack from its pinion, through the lever 64 and spring 67, effects only a given extent of disengaging movement of the rack, though the pivotal movement of the stop may be varied, depending on the force with which the carriage is returned and the distance that the spring-pressed plunger is

moved from its normal position by the impact between the stops, and that in the return movement of the pivoted stop to its normal position it will move independently of the rack a distance corresponding to the excess movement of the pivoted stop over what is required to disengage the rack and that consequently the rack will always reengage the pinion so as to start the carriage at the same point. In other words, notwithstanding the fact that the carriage may be moved to the right different distances beyond a normal arresting point, depending on the force of the return movement and that this movement will disengage the rack, the rack will, nevertheless, always reengage with the pinion so as to always start the carriage from a given point on the carriage scale or a given letter space position and not one, two or more rack teeth or letter space distances from said point. It will also be seen that the construction is such that the stop 50 is movably mounted on its support to effect the ringing of the alarm and the actuation of the line-lock mechanism; that, nevertheless, the same stop may be employed to coöperate with its spring buffer and associated mechanism to diminish the shock when the carriage is violently returned to begin a new line of writing and to automatically disengage the carriage from its feed mechanism so that the shock will not be transmitted to the feed rack or feed mechanism; that the function of the stop 50 to accomplish either purpose does not interfere with its function to accomplish the other purpose; that the spring buffer and alarm and line-lock mechanism is effective to coöperate with the pivoted stop at any point in the line of writing or in the travel of the carriage depending on the adjustment of the margin stops along the bar 33; that the rack is only raised a given distance no matter how far the pivoted stop may be turned by contact with the stop 37 and that the return movement of the pivoted stop from its extreme position may be effected in part independently of the rack so that the pivoted stop has almost attained the normal position before the rack is reengaged with its feed pinion and there is little chance, therefore, of the carriage being arrested at the wrong letter space position, by the rack engaging the pinion one tooth of the rack before, or one tooth behind the predetermined position it is intended the engagement with the pinion should take place; that the means for automatically shifting the rack out of engagement with its feed pinion does not interfere with the rack being released at any time by the rack release lever 28, and that the devices of my invention may be applied to existing typewriting machines such as the "Monarch" machine, for instance, without changing the structural features of said machine.

Various changes may be made and certain features may be employed without others.

What I claim as new and desire to secure by Letters Patent, is:—

5. 1. In a typewriting machine, the combination of a carriage, carriage feed mechanism, a stop on the carriage, a coöperating margin stop on the frame of the machine, and means controlled by one of said stops for disconnecting the carriage from its feed mechanism during the return movement of the carriage to the right.

2. In a typewriting machine, the combination of a carriage, carriage feed mechanism, 15 and stops which coöperate to limit the travel of the carriage in its movement to the right to begin a new line of writing, one of said stops being mounted to move in two directions on its support from a central normal 20 position, the movement of the stop in one direction being effective to disconnect the carriage from its feed mechanism and the movement of the stop in the other direction being ineffective to disconnect the carriage 25 from its feed mechanism.

3. In a typewriting machine, the combination of a carriage, carriage feed mechanism, stops which coöperate to limit the travel of the carriage in its return movement to begin 30 a new line of writing, one of said stops being mounted to move in two directions from a central normal position, the movement of the stop in one direction being effective to disconnect the carriage from its feed mechanism 35 and the movement of the stop in the other direction being ineffective to disconnect the carriage from its feed mechanism, and a spring which coöperates with one of said stops and affords a limited movement thereof 40 when the stops are brought into contact.

4. In a typewriting machine, the combination of a carriage, a margin stop, a second stop coöoperating with said margin stop for effecting an arrest of the carriage in its return 45 movement to begin a new line of writing, and a feed rack lifted by one of said stops when the stops are brought into coöperation.

5. In a typewriting machine, the combination of a carriage, a spring-pressed stop, a 50 coöperating margin stop, and a feed rack lifted and disengaged by said spring pressed stop.

6. In a typewriting machine, the combination of a carriage, margin and line stop mechanism comprising a stop that is adapted to move in two directions, and two coöperating stops that move said movable stop in two directions, the movement of the movable stop in one direction being effected by one of said 60 coöperating stops and being resisted by a spring to decrease the shock and the movement of the stop in the other direction being effected by the other coöperating stop and being effective to ring an alarm.

65 7. In a typewriting machine, the combina-

tion of a carriage, carriage feed mechanism, stops for limiting the movement of the carriage, one of said stops being movable for a limited distance independently of its support, and a spring that forms a connection between 70 said movable stop and the carriage feed mechanism, whereby said carriage feed mechanism is disconnected when said stop is moved.

8. In a typewriting machine, the combination of a carriage, a carriage feed rack, stops for limiting the movement of the carriage, one of said stops being movable for a limited distance independently of its support, and a spring that forms a connection between said 80 movable stop and the carriage feed rack to automatically move the rack to disconnect the carriage when the stops are brought into contact.

9. In a typewriting machine, the combination of a carriage, a carriage feed device, a coöperating feed rack, stops for limiting the movement of the carriage, one of said stops being inovable for a limited distance independently of its support, a spring that 85 resists the movement of the stop in one direction, and a spring that forms a connection between said movable stop and feed rack to automatically move the feed rack out of co-operation with said feed device when the 90 stops are brought into contact.

10. In a typewriting machine, the combination of a carriage, stops that limit the movement of said carriage, one of said stops having a movement independently of its support, a spring for restoring the independently movable stop to normal position on its support, a line lock and alarm bail actuated by said stop, and an independent spring that resists the movement of said stop in the 105 other direction.

11. In a typewriting machine, the combination of a carriage, stops that limit the movement of said carriage, one of said stops having a movement independently of its 110 support, a line lock and alarm bail actuated by the movement of said stop in one direction and a spring that resists the movement of said stop in a direction opposite that required to actuate said bail.

115 12. In a typewriting machine, the combination of a carriage, stops that limit the movement of the carriage, one of said stops having a limited movement independently of its support, an elastic buffer that resists 120 the movement of the movable stop in one direction and absorbs the shock between the stops, and a line lock and alarm mechanism that is actuated by the movement of said movable stop in the other direction.

125 13. In a typewriting machine, the combination of a carriage, carriage feed mechanism, stops that limit the movement of the carriage, one of said stops having a limited movement independently of its support, in- 130

termidiate connections between said movable stop and the carriage feed mechanism and which are effective to release the carriage from its feed mechanism by a movement in 5 one direction, an elastic buffer that resists the movement of the movable stop in one direction and absorbs the shock between the stops, and a line lock and alarm mechanism that is actuated by the movement of said 10 movable stop in the other direction.

14. In a typewriting machine, the combination of a carriage, carriage feed mechanism including a feed rack, stops to limit the movement of the carriage, said stops including a margin stop, a line stop and a stop that is movably mounted on its support and co-operates with the margin and line stops, an elastic buffer with which said movable stop co-operates in its movement in one direction, 15 and line lock and alarm mechanism which is actuated by the movement of the movable stop in the opposite direction.

15. In a typewriting machine, the combination of a carriage, carriage feed mechanism, and means controlled by the return movement of the carriage for automatically disconnecting the carriage feed mechanism.

16. In a typewriting machine, the combination of a carriage, carriage feed mechanism, stops to arrest the carriage in its return movement, and means for automatically disconnecting said carriage feed mechanism when the stops are brought into co-operation.

17. In a typewriting machine, the combination of a carriage, carriage feed mechanism, stops to arrest the carriage in its return movement, one of said stops being movable on its support, and means controlled by said movable stop to disconnect the carriage 35 feed mechanism when the movable stop is moved from its normal position by the contact of said stops.

18. In a typewriting machine, the combination of a carriage, carriage feed mechanism, stops to arrest the carriage in its return movement, one of said stops being movable on its support, means controlled by said movable stop to disconnect the carriage feed mechanism when the movable stop is moved 45 from its normal position by the contact of said stops, and an elastic buffer with which said movable stop co-operates to afford a limited movement of the movable stop when the stops are brought into co-operation and 50 to absorb the shock of the contacting stops.

19. In a typewriting machine, the combination of a carriage, carriage feed mechanism, stops for the carriage, one of said stops being movable on its support in two directions from the normal position, line lock and alarm mechanism actuated by the movement of the stop in one direction, and means controlled by the movement of the movable stop in the other direction for disconnecting 60 the carriage feed mechanism.

20. In a typewriting machine, the combination of a carriage, a feed rack therefor, stops to arrest the carriage in its return movement, one of said stops being movable by the impact between the stops, and means 70 controlled by the movable stop for elevating the rack and maintaining it elevated as long as the movable stop is maintained beyond its normal position by the other stop and for affording a lowering of the feed rack when the movable stop is restored to its normal position.

21. In a typewriting machine, the combination of a carriage, stops, including a pivoted stop in the form of an angular lever, and 80 an elastic buffer with which said angular lever co-operates in its movement in one direction and when the stops are brought into co-operation to arrest the carriage in its return movement.

22. In a typewriting machine, the combination of a carriage, carriage stops including a pivoted stop in the form of an angular lever, an elastic buffer with which said angular lever co-operates in its movement in one 90 direction and when the stops are brought into co-operation to arrest the carriage in its return movement, and line alarm and lock mechanism with which said angular lever co-operates.

23. In a typewriting machine, the combination of a carriage, carriage stops, including a pivoted stop in the form of an angular lever, an elastic buffer with which said angular lever co-operates in its movement in one 100 direction, and a line alarm and line lock actuating device with which said angular lever co-operates and which is actuated thereby in its movement in a direction opposite that resisted by the elastic buffer.

24. In a typewriting machine, the combination of a carriage, a carriage feed rack, a margin stop, a co-operating stop that is movable on its support, a lever that is moved by said movable stop and moves independently 110 thereof, and a spring between said lever and feed rack for elevating said feed rack.

25. In a typewriting machine, the combination of a carriage, a carriage feed rack, a margin stop, a co-operating stop that is movable on its support, an elastic buffer that co-operates with said movable stop and absorbs the shock of impact between the stops and affords a movement of said movable stop, a 115 lever that is moved by said movable stop and affords a movement independently thereof, and a spring between said lever and feed rack whereby said lever raises said feed rack.

26. In a typewriting machine, the combination of a carriage, a feed rack, a spring carried by said feed rack, a stop carried by said feed rack and against which the spring bears to limit its movement in one direction, and co-operating stops, one of said co-operating stops being movable on its support and op- 120 125 130

eratively connected with said spring to raise | a disengagement of the rack through said 65
said feed rack.

27. In a typewriting machine, the combination of a carriage, a feed rack, a spring carried by said feed rack, a stop against which the spring bears to limit its movement in one direction, coöperating stops, one of said coöperating stops being movable on its support and operatively connected with said spring 10 to raise the rack, and a spring which coöperates with said movable stop and absorbs the shock of impact between said stops.

28. In a typewriting machine, the combination of a carriage, a feed rack therefor, 15 stops, one of said stops being in the nature of a pivoted angle lever, a disengaging lever that is actuated by said angle lever, and operative connections between the disengaging lever and the feed rack.

29. In a typewriting machine, the combination of a carriage, a feed rack therefor, stops, one of said stops being in the nature of a pivoted angle lever, a disengaging lever that is actuated by said angle lever, and a 25 spring connected to the feed rack and with which said disengaging lever coöperates to disengage the rack.

30. In a typewriting machine, the combination of a carriage, a feed rack therefor, 30 stops, one of said stops being in the nature of a pivoted angle lever, a disengaging lever that is actuated by said angle lever, operative connections between the disengaging lever and the feed rack, and a spring that is 35 strained by the impact of the stops and which absorbs the shock.

31. In a typewriting machine, the combination of a carriage, a carriage feed mechanism, stops, means which afford an additional 40 movement of the carriage to the right after the stops have been brought into contact, and means for automatically disengaging the carriage from its feed mechanism by such additional movement.

32. In a typewriting machine, the combination of a carriage, carriage feed mechanism, stops, means which afford an additional movement of the carriage to the right after the stops have been brought into contact, 50 and means for automatically disengaging the carriage from its feed mechanism by such additional movement and automatically reconnecting the carriage to its feed mechanism when the carriage is restored to the point 55 where the stops were first brought into engagement.

33. In a typewriting machine, the combination of a carriage, a feed rack therefor, stops, for arresting the carriage in its return 60 movement, and carriage-disengaging means coöperative with said feed rack, one of said stops having a movement in one direction that does not affect the feed rack and a movement in another direction that effects

a disengagement of the rack through said 65 disengaging means.

34. In a typewriting machine, the combination of a carriage, a feed rack therefor, stops, for arresting the carriage in its return movement, and carriage-disengaging means 70 coöperative with said feed rack, one of said stops having a movement in one direction that does not affect the feed rack and a movement in another direction that effects a disengagement of the rack through said 75 disengaging means, and a spring buffer with which said movable stop coöperates.

35. In a typewriting machine, the combination of a carriage, a feed rack carried thereby, stops, one of said stops being pivoted to 80 the carriage, an auxiliary lever pivoted to the carriage and coöperating with the pivoted stop to be moved thereby and to afford a movement of the pivoted stop independently thereof, and operative connections between 85 said auxiliary lever and the feed rack.

36. In a typewriting machine, the combination of a carriage, a feed rack carried thereby, stops, one of said stops being pivoted to the carriage, an auxiliary lever pivoted to 90 the carriage and coöperating with the pivoted stop to be moved thereby and to afford a movement of the pivoted stop independently thereof, operative connections between 95 said auxiliary lever and the feed rack, and a spring buffer carried by the carriage and against which the pivoted stop bears.

37. In a typewriting machine, the combination of a carriage, a feed rack carried thereby, stops, one of said stops being in the nature of an angle lever that is pivoted to the carriage, an auxiliary lever pivoted to the carriage and coöperating with the pivoted stop to be moved thereby and to afford a movement of the pivoted stop independently 100 thereof, and a spring which forms an operative connection between said auxiliary lever and the feed rack.

38. In a typewriting machine, the combination of a carriage, a feed rack carried thereby, stops, one of said stops being in the nature of an angle lever that is pivoted to the carriage, an auxiliary lever pivoted to the carriage and coöperating with the pivoted stop to be moved thereby and to afford a 110 movement of the pivoted stop independently thereof, a spring which forms an operative connection between said auxiliary lever and the feed rack, and a spring buffer carried by the carriage and against which the pivoted 115 stop bears.

39. In a typewriting machine, the combination of a carriage, a feed rack carried thereby, stops, one of said stops being in the nature of an angle lever that is pivoted to the 125 carriage, an auxiliary lever pivoted to the carriage and coöperating with the pivoted stop to be moved thereby and to afford a

movement of the pivoted stop independently thereof, a spring which forms an operative connection between said auxiliary lever and the feed rack, a spring buffer carried by the carriage and against which the pivoted stop bears, and a bell ringing and line lock actuating device that is operated by said movable stop.

40. In a typewriting machine, the combination of a carriage, a feed rack therefor, stops, one of said stops being in the nature of a pivoted angle lever, one arm of which forms a stop member and the other arm of which constitutes an actuating member, an auxiliary lever coöperating with the actuating arm to be moved thereby in its movement in one direction and to be unaffected by its movement in an opposite direction, and operative connections between said feed rack and said auxiliary lever.

41. In a typewriting machine, the combination of a carriage, a feed rack therefor, stops, one of said stops being in the nature of a pivoted angle lever, one arm of which forms a stop member and the other arm of which constitutes an actuating member, an auxiliary lever coöperating with the actuating arm to be moved thereby in its movement in one direction and to be unaffected by its movement in an opposite direction, and operative connections between said feed rack and said auxiliary lever, and a spring buffer against which the pivoted stop bears.

42. In a typewriting machine, the combination of a carriage, a feed rack therefor, stops, one of said stops being in the nature of a pivoted angle lever, one arm of which forms a stop member and the other arm of which constitutes an actuating member, an auxiliary lever coöperating with the actuating arm to be moved thereby in its movement in one direction and to be unaffected by its movement in an opposite direction, and operative connections between said feed rack and said auxiliary lever, a spring buffer against which the pivoted stop bears, and a bell ringing and line lock actuating member that cooperates with the actuating member on said pivoted stop.

50 43. In a typewriting machine, the combination of a carriage, stops, one of said stops being pivoted to move in the direction of the travel of the carriage, and means for resiliently supporting the pivoted stop against such movement.

44. In a typewriting machine, the combination of a carriage, stops, one of said stops being mounted for independent movement on its support, and a spring buffer that operates directly with said last mentioned stop and absorbs the shock of the impact between the stops during the return movement of the carriage.

45. In a typewriting machine, the combi-

nation of a carriage, a carriage feed rack, co-operating stops for arresting the carriage in its return movement, one of said stops being mounted for independent movement on its support, and means for utilizing the independent movement of said stop to elevate the feed rack.

46. In a typewriting machine, the combination of a carriage, a carriage feed mechanism, stops, one of said stops being mounted for independent movement on its support, an alarm and line lock actuating device actuated by the independent movement of the movable stop in one direction, and means for utilizing the independent movement of said movable stop in the other direction to disconnect the carriage from its feed mechanism.

47. In a typewriting machine, the combination of a carriage, a carriage feed mechanism, stops, one of said stops being mounted for independent movement on its support, a spring buffer coöperating with said last-mentioned stop to absorb the shock of impact between certain of said stops, an alarm and line lock actuating device actuated by the independent movement of the movable stop in one direction, and means for utilizing the independent movement of said movable stop in the other direction to disconnect the carriage from its feed mechanism.

48. In a typewriting machine, the combination of a carriage, a feed rack therefor, a spring that extends in the direction of the length of the feed rack and which is secured at one end to the rack and is free at the other other end thereof, a pin for limiting the downward movement of said spring, stops, one of said stops being movably mounted on its support, and operative connections between said movable stop and said spring.

49. In a typewriting machine, the combination of a carriage, a step-by-step feed device for said carriage, a yielding buffer for arresting the carriage when it is returned to begin a new line, and means for automatically disconnecting said carriage from its step-by-step feed device when said buffer comes into operation.

50. In a typewriting machine, the combination of a carriage, a step-by-step feed device for said carriage, a yielding buffer for arresting said carriage when it is returned to begin a new line, and means for automatically disconnecting said carriage from its step-by-step feed device, said means being adapted to automatically restore the connection between the carriage and step-by-step feed device at a predetermined letter space position.

51. In a typewriting machine, the combination of a carriage, a step-by-step feed device for said carriage, yielding means for arresting said carriage when it is returned to begin a new line, said means being adapted to yield to a greater or less extent according to

the force with which said carriage is returned, and means for automatically disconnecting said carriage from its step-by-step feed device when said buffer comes into operation, 5 said means being adapted to automatically restore the connection between the carriage and its step-by-step feed device at the same letter space position whether said buffer has yielded much or little.

10 52. In a typewriting machine, the combination of a carriage, a feed rack mounted on said carriage, an escapement, a rotary member geared to said feed rack and controlled by said escapement, a yielding buffer for arresting 15 said carriage when it is returned to begin a new line, and means for automatically disconnecting said feed rack from said rotary member when said buffer comes into operation, said means being adapted to automatically 20 restore the connection between said feed rack and said rotary member whether the buffer has yielded much or little.

53. In a typewriting machine, the combination of a carriage, a step-by-step feed device for said carriage, a yielding buffer for arresting said carriage when it is returned to begin a new line, means for automatically disconnecting said carriage from its step-by-step feed device when said yielding means 25 comes into operation, said means being adapted to automatically restore the connection between said carriage and its step-by-step feed device at the same predetermined letter space position whether said yielding means 30

has been caused to yield much or little, and 35 adjustable means for said yielding means.

54. In a typewriting machine, the combination of a carriage, a feed rack mounted on said carriage, a step-by-step feed device controlling said feed rack, yielding means for arresting the carriage when it is returned to begin a new line, and means for affording to 40 said carriage and feed rack a motion in letter space feed direction after said carriage and rack have been arrested by said yielding means, said means being adapted to arrest the carriage at the same letter space position whether said yielding means has been caused to yield much or little.

55. In a typewriting machine, the combination of a carriage, a feed rack mounted on said carriage, means including an adjustable margin stop for yieldingly arresting said carriage and its feed rack when they are returned to begin a new line, said means being adapted to yield much or little according to the force with which the carriage is returned and to finally arrest said carriage at a letter space position determined by the adjustment of said margin stop. 55

Signed at Syracuse, in the county of Onondaga, and State of New York, this 24th day of November A. D. 1905. 60
